[57] **ABSTRACT**

A rectangular waveguide dimensioned to propagate the TE₁₀ mode includes at each end of the waveguide terminations for terminating the TE₂₀ mode comprising slotted tapered ridges with lossy cavities closing the slots.

FIG. 1

FIG. 2

FIG. 3

BROADBAND WAVEGUIDE WITH MEANS FOR SUPPRESSING TE₂₀ MODE

BACKGROUND OF THE INVENTION

The present invention relates to broadband waveguides and more particularly concerns a novel broadband waveguide capable of efficiently transmitting microwave power over a relatively broad range of frequencies while avoiding overly critical dimension tolerances. The invention suppresses the undesired TE₂₀ mode without appreciably affecting the desired TE₁₀ mode.

It is usually preferred to operate a rectangular waveguide in the TE₁₀ mode in which the electric field is parallel to the narrow walls with a maximum midway between them. A serious limitation for broadband operation is the occurrence of the TE₂₀ mode in which the electric field is also parallel to the narrow walls but is zero both at the center and the narrow walls and oppositely phased in the two halves of the guide. In terms of results, the transmission loss characteristic of a rectangular waveguide is characterized by spikes at frequencies where the TE₂₀ mode becomes significant. One approach to suppressing the TE₂₀ mode is to form the top and bottom broad walls with lengthwise slots midway between the narrow walls, thereby interrupting the current for the TE₂₀ mode without disturbing the TE₁₀ mode because the current for the latter mode is zero there. Radiation will occur from the slot, but the radiation may be reduced by backing the slot with a cavity having lossy material. This approach is costly, complicated and presents especially great problems when the waveguide must follow a number of bends and twists.

A ridged waveguide may be used for propagating a broad band of microwave frequencies; however, such waveguides have a number of disadvantages. Dimensions are more critical and losses relatively high. Moreover, the relatively close spacing in the ridge region limits the amount of power that may be transmitted. The criticality of dimensions is an especially serious problem when the waveguide must follow a number of twists and bends.

Accordingly, it is an important object of the invention to provide a broadband rectangular waveguide that eliminates one or more of the disadvantages enumerated above.

It is a further object of the invention to achieve the preceding object with a rectangular waveguide capable of efficiently transmitting microwave energy over a broad range of frequencies over a relatively long path that may include a number of twists and bends.

It is still a further object of the invention to achieve one or more of the preceding objects with structure that is relatively free from complexity.

It is a further object of the invention to achieve one or more of the preceding objects with negligible leakage radiation.

SUMMARY OF THE INVENTION

According to the invention, a rectangular waveguide includes means at least at one end for terminating the TE₂₀ mode, preferably comprising slotted tapered ridges with lossy cavities closing the slot in a section that also matches a ridged waveguide to the rectangular waveguide.

Numerous other features, objects and advantages of the invention will become apparent from the following specification when read in connection with the accompanying drawing in which:

BRIEF DESCRIPTION OF THE DRAWING

FIG. 1 is a top view of an embodiment of the invention;

FIG. 2 is a transverse section through section 2-2 of FIG. 1; and

FIG. 3 is a longitudinal section through section 3-3 of FIG. 1.

DETAILED DESCRIPTION OF PREFERRED EMBODIMENTS

With reference now to the drawing and more particularly FIG. 1 thereof, there is shown a top view of a waveguide according to the invention. A long run of rectangular waveguide 11 is coupled to short runs of double ridged waveguides 12 and 13, respectively, by identical transition sections 14 and 15 having central longitudinal slots 16 and 17, respectively, filled with tapered wedges of lossy material 18 and 19, respectively, for dissipating energy in the TE₂₀ mode covered by mating conducting plates 18' and 19', respectively.

Referring to FIG. 2, there is shown a view through section 2-2 of FIG. 1. The transition section 14 includes upper and lower gradually tapering ridges 21 and 22, respectively, with upper ridge 21 formed with the slot 16 for interfering with the current in the TE₂₀ mode without appreciably affecting the current in the TE₁₀ mode. While only an upper slot 16 is shown, there could be a lower slot if desired in a particular situation.

Referring to FIG. 3, there is shown a longitudinal sectional view through section 3-3 of FIG. 1 illustrating how tapered ridges 21 and 22 taper from zero depths at a rectangular waveguide 11 to a depth corresponding to the depth of the ridges in double-ridged waveguide 12.

Having generally described a preferred embodiment of the invention, certain preferred dimensions will be defined. If the width of the rectangular guide is a and the height b , $a \approx 2\sqrt{2}b$. The transition section is typically a wavelength or more at the lowest frequency of the range to be transmitted. The ridge elements are tapered because a TE₁₀ wave should preferably not see an abrupt change. The slot depth is tapered from zero to max so a TE₂₀ wave preferably sees no abrupt change. The lossy cavities are typically substantially the same length as the slots. The slot length is typically greater than a wavelength at the low frequency end of the band to be propagated. The slot width is less than the ridge width, typically 20 percent of the ridge width. The ridge width is typically $a/4$. Those skilled in the art may use various techniques to minimize the VSWR over the frequency range of interest. The invention may typically intercouple RG52 rectangular waveguide with WRD 750 D24 ridged waveguide.

While the tapered transition section is preferred to provide a good match between ridged and rectangular waveguides for the TE₁₀ mode, the principles of the invention may be embodied with a direct connection between the ridged and rectangular guides. At least one of the ridges would be slotted for a wavelength or more from the junction with the rectangular guide at the low-

est frequency to be transmitted and backed by a lossy cavity.

The specific structure described herein is only by way of example for illustrating the best mode now contemplated for practicing the invention. Those skilled in the art may use other techniques for attenuating the TE₂₀ mode at each end of the rectangular waveguide within the principles of the invention. Since those skilled in the art may now make numerous other uses and modifications of and departures from the specific embodiments described herein, the invention is to be construed as embracing each and every novel feature and novel combination of features present in or possessed by the apparatus and techniques herein disclosed and limited solely by the spirit and scope of the amended claims.

What is claimed is:

1. Waveguide apparatus comprising,

1. Waveguide apparatus comprising:
a rectangular waveguide dimensioned to propagate energy in the TE_{10} mode over a predetermined frequency range,
at least one other waveguide coupled to one end of said rectangular waveguide,
and means coupled to said one end for attenuating the TE_{20} mode with said frequency range without appreciably affecting the transmission of the TE_{10} mode,
said at least one other waveguide comprising a ridged waveguide and said means coupled to said one end comprising a tapered rectangular waveguide section formed with a tapered slotted central ridge intercoupling said rectangular waveguide and said ridged waveguide with lossy material coupled to

the slot in said tapered slotted central ridge.
2. Waveguide apparatus in accordance with claim 1 and further comprising,

a ridged waveguide coupled to the other end of said rectangular waveguide,
and means coupled to said other end of said rectangular waveguide for attenuating said TE_{20} mode without appreciably affecting the transmission of the TE_{10} mode.

3. Waveguide apparatus in accordance with claim 1 wherein said means coupled to said one end comprises said slot adjacent to said one end longitudinally and symmetrically aligned in the broad wall of a waveguide coupling section substantially where the TE_{20} mode current is a maximum.

4. Waveguide apparatus in accordance with claim 1 wherein said lossy material fills said slot for dissipating energy in said TE_{20} mode.

5. Waveguide apparatus in accordance with claim 1 wherein the length of said slot is greater than a wavelength at the low frequency end of said predetermined frequency range.

6. Waveguide apparatus in accordance with claim 5, wherein the width of said slot is substantially 20 percent of the width of said ridge.

7. Waveguide apparatus in accordance with claim 6 wherein the width of said ridge is substantially one-fourth the width of said rectangular waveguide.

8. Waveguide apparatus in accordance with claim 7 wherein said lossy material substantially fills said slot for dissipating energy in said TE_{20} mode.
